UNITED STATES PATENT OFFICE

WINTHROP K. HOWE, OF ROCHESTER, NEW YORK, ASSIGNOR TO GENERAL RAILWAY SIGNAL COMPANY, OF ROCHESTER, NEW YORK

BRAKE FOR RAILROAD SWITCH MACHINES

Application filed October 14, 1929. Serial No. 399,549.

This invention relates to devices used for the control of railroad track switches, and more particularly pertains to a mechanical brake to be used with switch machines operating such switches.

It is found in practice to be an essential factor of safety, that no movement of a track switch should be allowed except under authorized control. In some cases however, the 10 switch points are operated to the desired extreme position with the switch machine failing to lock the track switch, due to the opening of an over-load device, the failure of parts, or the like, which condition results 15 in the display of a stop indication by the governing signal. But the tower operator, or other official, desiring to facilitate the movement of traffic, orders the train to proceed under flag, that is, send a flagman ahead 20 of the train which then proceeds over the "apparently locked" switch points.

Such a case as pointed out above, is not so dangerous with the so called trailing point moves of trains, while the facing point moves 25 produce a very undesirable hazard, in that the passage of the train produces a vibration and weaving of the track rails which may open the switch points enough to engage a thin car wheel flange causing a split train.

One object of the present invention is to provide means whereby such a contingency, as pointed out above, shall be provided for by the use of a mechanical brake, which brake is effective to prevent movement of the switch 30 points at all times when the track switch is unlocked and its controlling switch machine motor is not supplied with authorized control power.

Other objects, purposes and characteristic 40 features will be in part obvious from the accompanying drawings and in part pointed out as the description of the invention progresses.

In describing the invention in detail, reference will be made to the accompanying drawings, in which like reference characters indicate corresponding parts in the several views, and in which:—

Fig. 1 is a diagrammatic representation of 50 a motor of a switch machine and the switch

machine controlling mechanisms for a track switch with the brake of the present invention shown interposed between the switch machine motor and the mechanisms which are controlled thereby;

Fig. 2 is an end view of a mechanical brake shown as one specific embodiment of the present invention with parts shown in section as taken on the line 2—2 of Fig. 3;

Fig. 3 is a cross section of the mechanical 60 brake of the present invention taken on the line 3—3 of Fig. 2.

With reference to Fig. 1 of the drawings, there is shown in a diagrammatic manner a track switch TS controlled by any suitable 65 switch machine, such as set forth in my Patent No. 1,466,903, dated September 4, 1923, with the brake B, as the specific embodiment 70 of the present invention, interposed between the motor M and the various mechanisms of the switch machine. As the operation and construction of such a switch machine is completely disclosed in my above referred to patent, it is deemed unnecessary to describe the 75 operation and construction of the switch machine, other than is necessary to explain the operation of the present invention.

The motor M may be controlled in any well known manner, for example, as set forth in my Patent No. 1,550,611, dated August 18, 80 1925, and is shown as controlled over the normal and reverse control wires N and R in conjunction with a common wire C (see Fig. 1). The torque produced by the motor M during 85 operation, is transmitted through the brake B to the pinion 1 which meshes with a bevel gear 2. This bevel gear 2 is connected with a friction clutch K, which in turn is connected to the pinion 3, which pinion meshes with a gear 4. The gear 4 drives a pinion 5, 90 which in turn operates the main drive gear 6 of the switch machine.

The initial movement of the main drive gear 6 in either a reverse or a normal direction, that is, in a direction to control the track 95 switch TS to a normal or to a reverse position respectively, controls the lock plunger LP through a considerable distance before a lock dog LD^a disengages a throw-bar TB and before the lock dog LD^b disengages the lock 100

rods LR¹ and LR², at which time the main drive gear 6 operates the throw-bar TB to an opposite extreme position. The movement of the throw-bar TB operates the track switch 5 TS from an extreme normal position to an extreme reverse position, which movement also operates the lock rods LR¹ and LR² to reverse positions. With the throw bar TB and the lock rods LR¹ and LR² in reverse positions, the main drive gear 6 continues rotation, which moves the lock plunger LP to such a position that the lock dog LD^a again engages the throw-bar TB and the lock dog LD^b again engages the lock rods LR¹ and LR².

15 From the above description, it is obvious that the motor M can only operate the track switch TS at such times that the track switch is unlocked, and conversely, any force applied to the track switch can only tend to operate 20 the switch machine mechanism at such times that the track switch is unlocked. Thus, the provision of the brake B which permits the motor M to operate the track switch TS and which prevents the track switch from operating 25 the motor, accomplishes the desired result in that the track switch is prevented from movement at all times during which power is not applied to the switch machine motor.

With reference to Fig. 3, a brake drum BD 30 is provided as integral with the motor frame 7, and is also suitably joined with a portion of the switch machine frame 8. A motor shaft 9 passes through and is journaled in the motor frame 7. This motor shaft 9 furnishes a bearing for the pinion 1 which meshes with the gear 2. Two brake shoes 10 and 11 are secured to the pinion 1 by the pins 12 in such a manner that two springs 13 and 14 expand the brake shoes 10 and 11 until brake linings 15 and 16 come into contact with the braking surface of the brake drum BD. The pivot points furnished by the pins 12 are in such positions that the spring 13 tends to bias or force the brake shoe 11 against the brake drum BD, while the spring 14 tends to bias or force the brake shoe 10 against the brake drum BD (see Fig. 2). With such an arrangement, as torque is applied to the pinion 1, it cannot rotate due to the braking effect of the brake shoes 10 and 11.

To accomplish the compression of the springs 13 and 14 and to allow the torque applied to the shaft 9 to be transmitted to the pinion 1, a drive member 17 is keyed to the shaft 9 by a key member 24 and is further secured by a pin 25 (see Fig. 3). This drive member 17 has arms 17^a and 17^b which serve as pivot points for links 18 and 19, attached to 60 their respective arm supports by means of pins 20 and 21. These links 18 and 19 are pivotally attached to the brake shoes 10 and 11 respectively at intermediate points between the pivot points 12 and the points at which 65 the springs 13 and 14 apply expanding pres-

sure to their respective brake shoes (see Fig. 2).

When torque is applied to the shaft 9 by the motor M in either direction, forces are transmitted through the links 18 and 19 which are divided into component forces, so that certain compressing components tend to compress the springs 13 and 14, and certain other rotational components tend to rotate the brake shoes 10 and 11 in a direction depending upon the direction of the torque provided by the motor M. It is further seen, when the compressing component forces are of sufficient value to compress the springs 13 and 14, that the braking effect is eliminated and the pinion 1 is caused to rotate with the brake shoes 10 and 11 in a direction in accordance therewith, thus controlling the track switch TS to a corresponding position.

The component forces causing the compression of the brake shoes 10 and 11 against the bias of the springs 13 and 14, continues to compress these brake shoes so that they come into contact with the arms 17^a and 17^b of the drive member 17. Such a position is maintained by the brake shoes 10 and 11 during the operation of the motor M, with the brake shoes expanding and assuming a braking position against the brake drum BD as soon as the motor M ceases to receive power to 95 drive the load.

Thus, when the track switch TS is unlocked, it is prevented from movement if the governing motor is not supplied with power, due to the brake of the present invention 100 which is normally biased to a braking condition. However, if the governing motor is energized sufficient to normally operate the switch machine, the brake is first released and then continuously held in a released condition 105 as long as an active driving torque is supplied to the switch machine.

It is obvious that the mechanical brake of the present invention may be used with other types of switch machines than the specific type shown. Also, other applications of such a brake could be made, such as use with a car retarder mechanism or the like, or in other such cases where there is a driven element and a driving element.

Having described one specific embodiment of a mechanical brake constructed according to the present invention, it is to be understood that many alterations, modifications and adaptations may be applied to the present invention to meet the requirements of practice without departing from the spirit or scope of the invention as set forth in the appended claims.

Having described my invention, I now 125 claim:-

1. For use with a railroad track switch and a power driven switch machine, a mechanical brake including, a fixed brake drum, two brake shoes within said fixed brake drum 130

biased to engage said brake drum, means disengaging said brake shoes from said brake drum upon application of power to said switch machine including, a power driven
5 shaft of said switch machine, a plurality of arms upon said power driven shaft, and means movably connecting said arms to said brake shoes, whereby rotation of said shaft in either direction in respect to said brake
10 shoes disengages said brake shoes from said brake drum, and means operably causing said brake shoes to rotate with said shaft after said braking effect has been eliminated, including stops provided by said brake shoes
15 and engaging said arms on said power driven shaft.

2. For use with a track switch for railroads and a power driven switch machine, a mechanical brake including, a fixed brake
20 drum, a pinion drive member, two brake shoes pivotally attached to said pinion drive member, two coil springs biasing said brake shoes to engage said fixed brake drum, a power driven shaft, two drive arms on said
25 power driven shaft, two links with each of said links pivotally attached respectively to one of said drive arms and pivotally attached to one of said brake shoes respectively, whereby said power driven shaft can
30 operate said pinion drive member, and whereby said pinion drive member cannot operate said power driven shaft.

3. For use with a track switch for railroads and a power driven switch machine, a mechanical brake including, a fixed brake
35 drum, a pinion drive member, two brake shoes within said fixed brake drum having opposite extreme ends pivotally attached to said pinion drive member, two coil springs
40 each of which bias one of said brake shoes to engage said brake drum, a power driven shaft, two drive arms extending for a predetermined distance toward said brake shoes from said power driven shaft, two links each
45 of which is pivotally attached to the one of said brake shoes opposite said drive arm, whereby said power driven shaft can compress said springs until said brake shoes come into contact with said drive arms, and whereby
50 by torque on said power driven shaft will operate said pinion drive member with a certain minimum value of load reaction present upon said pinion drive member, and whereby said pinion drive member cannot operate said power driven shaft.

In testimony whereof I affix my signature.
WINTHROP K. HOWE.
